UNITED STATES PATENT OFFICE

2,644,258

HINGE AND GATE CONSTRUCTION

Edwin Gillette, Los Angeles, Calif.

Application December 11, 1950, Serial No. 200,230

7 Claims. (Cl. 39—82)

1

The present invention relates to an improved gate construction particularly useful with large, heavy, bulky gates.

In general the present invention contemplates a gate construction in which a caster is mounted on the free end of the gate, with the caster at all times engaging the pavement when and as the gate is being moved to open and closed positions.

Usually, when a caster is placed on the free end of a gate, the caster touches only the "high spots" of the pavement and does not follow the dips or unevenness in the pavement, with the result that at some time all of the gate is supported on the hinge structure instead of being partially supported on the pavement or ground as intended.

The present invention provides improved means wherein at all times the caster follows the uneven portions of the ground or pavement.

It is therefore an object of this invention to provide a gate supporting structure of this character for producing the aforementioned result.

A specific object of this invention is to provide improved supporting means for a gate which is characterized by the fact that the gate itself is prevented from wobbling yet is allowed to follow unevenness in the ground, using a mounting structure which is characterized by its simplicity and inexpensive nature.

Another object of this invention is to provide an improved hinge structure which incorporates generally an elongated channel iron with means for hinging the same so that it may swing about a generally vertical axis, the channel iron being adapted to receive a pivot pin through aligned apertured portions in the parallel extending plates of such channel iron.

Another object of the present invention is to provide an improved supporting means for a gate having caster means mounted on the free end of such gate, the invention being characterized by the fact that such supporting means allows the caster to always contact the pavement or ground over which the gate is swung regardless of whether or not such pavement or ground may be inclined with respect to the horizontal plane.

The features of the present invention which are believed to be novel are set forth with particularity in the appended claims. This invention itself, both as to its organization and manner of operation, together with further objects and advantages thereof, may be best understood by reference to the following description taken

2

in connection with the accompanying drawings in which:

Figure 1 is a view in front elevation of a gate incorporating the novel mounting structure embodying features of the present invention, a part of the mounting structure being fragmented to show internal structure and the gate being shown in closed position;

Figure 2 is an enlarged sectional view taken substantially on the line 2—2 of Figure 1; and

Figure 3 is a perspective view showing the gate itself detached from its mounting structure, although this figure does show the mounting pin.

In the present arrangement, a channel iron 10 of special dimensions is hinged at two places, in the conventional manner, by means of conventional two-part hinges 11, 12, one part of such hinges 11, 12 being imbedded in the masonry structure 14, for example, or bolted to a wooden support, and the other part of such hinges 11, 12 being welded to the channel iron 10. A single pivot pin 15 passes through an apertured portion 16A in an end of the wooden gate 16 so that this gate is at all times free to pivot about the axis of this pin 15 whereby at all times a part of the weight of the gate is supported on the caster 17 affixed to the lower portion of the free end of the gate.

Preferably a metal insert 18 in the form of a tube or bushing aligns the apertured portion 16A of the gate 16 to prevent undue wear.

The pivot pin 15 actually comprises a bolt or rivet with heads on opposite ends thereof engaging the parallel extending plates of the channel iron 10 to prevent accidental removal of the pivot pin 15.

Preferably the inner end 16B of the gate 16 is formed arcuate in shape to provide adequate clearance for pivoted movement about the pin 15. In actual practice, for gates having length in the order of 12 feet, the pin 15 may comprise a $\frac{3}{4}$ inch bolt and the spacing between the parallel plates of the channel iron 10 may, for example, be $1\frac{1}{8}$ inches while preferably the widths of such parallel plates are in the order of 12 inches to provide extended surfaces against which the inner gate may abut when and as it tends to sway about, for example, a horizontal axis passing through the axis of the pivot pin 15.

It is observed that the gate mounting structure is relatively simple, of rather pleasing appearance considering the function which it achieves, such pleasing appearance being imparted to a large extent by the fact that the channel iron 10 is effectively a box around the inner

end of the gate element; and of equal importance is the fact that the channel iron serves as a protective element to prevent extraneous objects from becoming lodged between the gate and its mounting to thereby minimize the likelihood of trouble in use of the gate and further such "box" construction prevents to a large extent accidental injuries to persons or animals.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a gate construction of the character described, a gate element, an elongated channel iron extending vertically substantially the full height of said gate element with the inner end of the gate element disposed in said channel iron, hinge means mounted on said channel iron, a single pivot pin passing through alined apertured portions in the parallel extended plates of said channel iron and an apertured portion in said gate element, said pivot pin extending generally horizontally, and a caster mounted on the free end of said gate element, the inner walls of said channel member being spaced from said inner gate end to permit pivoting of said gate about said pivot pin with said extended plates serving as a stop and preventing undue pivoting movement of said gate element about an axis which passes radially through said pivot pin.

2. In a gate construction of the character described, a gate element, a caster mounted on the free end of said gate element, and means mounted near the hinged end of said gate element permitting the caster to always follow unevenness in the ground or pavement, said means comprising a channel iron embracing the inner end of said gate element with a single pivot pin mounted on said channel iron and passing through apertured portions in said channel iron and said gate element, the inner walls of said channel iron being spaced from said gate end to permit pivoting of said gate about said pivot pin, with the parallel extending plates of said channel iron serving as a stop and preventing undue pivoting movement of said gate element about an axis which passes radially through said pivot pin.

3. In a gate construction of the character described, a gate element, a caster mounted on the free end of said gate element, a channel iron, means pivotally supporting said channel iron for movement about generally a vertical axis, the inner end of said gate element being embraced by said channel iron, and a pivot pin mounted on said channel iron and extending through the apertured portions of the channel iron and said gate element, the inner edge of said gate element being generally arcuate in shape and spaced from

said channel iron to provide clearance for permitting pivotal movement about said pivot pin whereby at all times said caster follows unevenness in the ground or pavement when and as said gate element is being moved from open to closed position and vice versa.

4. In a gate construction of the character described, a gate element, a caster mounted on the free end of said gate element, a channel iron, means pivotally mounting said channel iron for swinging movement generally about a vertical axis, the inner end of said gate element being snugly confined within said channel iron, a single pivot pin passing through opposite plates of said channel iron and through an apertured portion in said gate element, said channel iron having relatively large extended plates snugly embracing the inner edge of said gate element to prevent swaying of said gate element about an axis passing generally parallel to the axis of said gate element, and the inner edge of said gate element being generally arcuate to provide clearance whereby said inner end may pivot within said channel iron about the axis of said pivot pin.
5. In a gate structure, the subcombination comprising an elongated channel iron, means on said channel iron adapting the same for pivotal movement about a vertical axis, which corresponds to the longitudinal axis of the channel iron, and means adapting said channel iron to support a gate for pivotal movement about a generally horizontal axis with the inner walls of said channel iron spaced from said gate to permit pivotal movement of said gate about the last mentioned means and with the parallel spaced element of said channel iron serving as stops for preventing undue swaying of said gate about an axis which passes radially through said horizontal axis, about which said gate is pivoted.
6. In a gate structure, the subcombination comprising an elongated channel member, spaced hinge means for maintaining the longitudinal axis of said channel member generally vertical and for pivoting said channel member about a vertical axis parallel to said longitudinal axis, and a pivot pin passing through opposed plates of said channel member.
7. The arrangement set forth in claim 6 in which said pivot pin passes through said plates at a point substantially midway between the extremities of said channel member.

EDWIN GILLETTE.
